UNITED STATES PATENT OFFICE.

JOHN W. NESMITH, OF DENVER, COLORADO, ASSIGNOR TO THE COLORADO IRON WORKS, OF SAME PLACE.

BLAST-FURNACE.

SPECIFICATION forming part of Letters Patent No. 512,053, dated January 2, 1894.

Application filed April 24, 1893. Serial No. 471,644. (No model.)

To all whom it may concern:

Be it known that I, JOHN W. NESMITH, a citizen of the United States of America, residing at Denver, in the county of Arapahoe and 5 State of Colorado, have invented certain new and useful Improvements in Blast-Furnaces, of which the following is a specification.

The object of this invention is to provide means for supporting and securely holding in 10 place the lower ends of the water jackets which form the lower zone of the furnaces to prevent their bulging out under the pressure of the molten contents of the furnace.

In the drawing the figure is a vertical section 15 view of a furnace constructed in accordance with my invention.

In the drawing C, C, are the sectional water jackets forming the lower zone of the furnace and upon which the inner lining F rests. 20 These water jackets are supported by a plate D preferably constructed of cast-iron, supported in any suitable manner, but preferably by jack screws B, B, and provided with an upwardly extending rim R, R which may 25 or may not be continuous around the furnace, and is suitably shaped to prevent the lower ends of the sectional water jackets C, C, forming the lower zone of the furnace, from bulging or moving out under the pressure 30 of the contents of the furnace. This plate may be strengthened by any suitable arrangement of ribs, as at S, S. It is made to form substantially a continuous piece. No special precautions are necessary to make

tight joints between the several parts, as the 35 molten contents of the furnace flowing into such interstices will chill and form a tight and effective working joint of itself, and prevent any further escape of the molten contents. 40

It should be understood that I do not claim as new, and am making no endeavor to secure by Letters Patent, any construction of a blast furnace in which the bottom is made in several parts; certain of the parts, particularly those immediately below the interior of the furnace being hinged to the other parts and arranged to swing down and expose the interior of the furnace. Nor do I claim as 45 new, any construction of a blast furnace, in 50 which a continuous bottom plate is permanently fastened to the lower end of the water jacket by bolts or rivets.

I claim—

In combination with a stack, supports 55 therefor, a lining for said stack, water jackets forming the lower zone of the furnace and a continuous plate D forming the bottom of the said water jacket having a flange encircling the lower end of said jacket, said bottom being 60 removably supported, substantially as described.

In testimony whereof I affix my signature in presence of two witnesses.

JOHN W. NESMITH.
